APPARATUS FOR APPLYING AND REMOVING MAKE-UP

Antoine Francois Peyron, 4 Rue de Londres,
Paris, France

Filed May 25, 1959, Ser. No. 56,039

Term of patent 14 years

(Cl. D86—10)

FIG-2-

FIG-3-

FIG-1-

FIG-4-

FIG-5

Fig. 1 is a front elevational view of an apparatus for applying and removing make-up showing my new design;

Fig. 2 is a top plan view thereof;

Fig. 3 is a left side elevational view;

Fig. 4 is a right side elevational view; and

Fig. 5 is a rear elevational view thereof.

The essential features of my design reside in the portions shown in solid lines on the drawing.

I claim:

The ornamental design for an apparatus for applying and removing make-up, as shown and described.
